UNITED STATES PATENT OFFICE

2,515,523

FLASK OR TEST TUBE HOLDER

Christy Mancino, Youngstown, Ohio, assignor to
 Carnegie-Illinois Steel Corporation, a corpora-
 tion of New Jersey

Application May 8, 1947, Serial No. 746,743

1 Claim. (Cl. 248—309)

1

This invention relates to improvements in holders for flasks, test tubes, or similar articles.

In laboratory work, flasks, test tubes and other containers are frequently suspended in relation to other apparatus, as for example, over the flame of a Bunsen burner. Spring clamps or pincer-like devices have customarily been employed for such purposes, but are inefficient and unreliable.

It is the principal object of my invention to provide a holder which readily and securely mounts and supports containers of the character stated without the necessity for adjustment or spring pressure.

Additional objects and advantages will become apparent from the following description, taken in connection with the accompanying drawing, wherein:

Fig. 1 is an elevational view of a holder embodying my invention, showing a flask supported thereby; and

Fig. 2 is a perspective view of the holder.

Referring to the drawing, the holder of my invention includes an upper member 2 and a lower member 3 respectively having free terminals 4 and 5 spaced apart vertically. As indicated, the holder may be formed of two members welded or otherwise secured together at 6. One end of the upper member 2 may be slotted or drilled as at 7 for attachment by bolt 8 to a support 9, which, for example, may comprise a part of a laboratory bench or table.

The terminal 4 of the upper member 2 is slotted at 10 to form an open bifurcated end to receive the neck of a flask or other container 11. Collars or heads 12 are provided on the flasks or containers, and overlie the spaced arms 13 on either side of the slot 10 to support the flask or container, the terminals 14 of said arms 13 being upturned to prevent accidental sliding disengagement of the collar 12.

Lower member 3 is proportioned to have its terminal 5 engage the flask or container 11 at one

2

side thereof in a plane beneath and spaced from that of the end 4 of member 2, thereby providing a steady rest for the flask or container in an upright position. The said terminal 5 is preferably formed with an outer concave edge or surface 15 to partially embrace the flask or container.

From the foregoing, it will be seen that my holder may be fixed to a suitable support, and flasks or containers readily applied thereto and removed therefrom in relation to a burner 16 or other device, by the simple expedient of engaging the flask or container with the bifurcated end 4 and rest 5, the lugs 14 preventing lateral disengagement of the supported flask or container from the slot 10.

Various changes and modifications are contemplated within the scope of the following claim.

I claim:

A holder for flasks or the like comprising an arm 20 adapted to be so mounted on a support as to extend laterally therefrom, the outer end of the arm being bifurcated forming two spaced prongs adapted to embrace the neck of a flask, a lug projecting upwardly from the end of each prong 25 adapted to retain a flask on the holder, and a bracing member extending downwardly from said arm adapted to engage the flask below said prongs.

CHRISTY MANCINO.
